(57) CLAIM

An ornamental design for an animated docking system for consumer electronics, as shown and described.

DESCRIPTION

FIG. 1 is a front view of an animated docking system for consumer electronics showing our new design;

FIG. 2 is rear view thereof;

FIG. 3 is a right side view thereof, the left side being a mirror image;

FIG. 4 is a top view thereof; and,

FIG. 5 is a bottom view thereof.
